UNITED STATES PATENT OFFICE.

HENRY W. WELLS, OF VAN NUYS, CALIFORNIA.

GAME-CARDS.

1,292,184.

Specification of Letters Patent.

Patented Jan. 21, 1919.

Application filed May 7, 1917. Serial No. 166,957.

To all whom it may concern:

Be it known that I, HENRY W. WELLS, a citizen of the United States, residing at Van Nuys, in the county of Los Angeles and 5 State of California, have invented certain new and useful Improvements in Game-Cards, of which the following is a specification.

This invention relates to game devices and 10 has as its object to provide a pack of playing cards with which interesting and instructive games may be played.

More specifically, the invention aims to provide a pack of playing cards so arranged 15 that in the playing of games with said pack the players will become familiar with data concerning the States of the United States and the District of Columbia, such, for example, the State boundaries, population, 20 etc.

The invention also contemplates, as a novel feature in game devices of this class, the provision upon the reverse face of each card of a symbol, design, or the like, such, 25 for example, as a representation of the State seal, to indicate to the players other than the player holding the said card, the character of the card.

In the accompanying drawings:

30 Figure 1 is a plan view of a hand of the cards, the view illustrating the reverse faces of the cards comprising the hand;

Fig. 2 is a plan view of the obverse face of that card of the deck known as the "District" card;

Figs. 3, 4, 5 and 6 are plan views of the cards of one book;

Figs. 7, 8, 9 and 10 are plan views of the cards of another book;

40 Figs. 11, 12, 13 and 14 are plan views of the cards comprising a third book.

Each card of the deck with the exception of the "District" card represents some one State of the Union and the forty-eight State 45 cards are divided into twelve books each comprising four cards, the "District" card making the forty-ninth or odd card. The drawings illustrate three books of the cards and the arrangement of the remaining books 50 will be understood therefrom, and inasmuch as the principle involved is the same in each book it is thought that a description of the cards comprising the first book will suffice. This particular book is illustrated in Figs. 3, 4, 5 and 6 of the drawings, and in the 55 said figures the numeral 1 indicates the obverse face of each card. Printed upon the said obverse face of each card comprising this book, at the upper left hand corner, is the number 1, and this number in the four 60 cards shown in Figs. 3, 4, 5 and 6 is printed respectively in red, blue, black and yellow, the number 1 being indicated by the numeral 2. While these colors are preferred it will be understood that the said number 1 may 65 be printed in other colors if desired so long as each card bears a different color. At this point it may be stated that the cards comprising the second book, which cards are illustrated in Figs. 7, 8, 9 and 10 of the 70 drawings, bear the number 2 printed in correspondingly different colors and that the cards of the other books bearing numbers corresponding to the number of the book; thus the cards comprising the twelfth book 75 will each bear the number 12. A rectangular border 3 is also printed upon the obverse face of each card and upon the said face of each card above the border 3 there are printed in full or in an abbreviated form, 80 the names of the State cards required to complete that particular book. For example, the card shown in Fig. 3 of the drawings represents the State of California and inasmuch as the book embraces the State 85 cards, California, Alabama, Arkansas and Arizona, the said card shown in Fig. 3 will bear the State names, Alabama, Arizona and Arkansas, as indicated by the numeral 4, these three State cards in combination with 90 the card shown in Fig. 3, or, in other words, the card representing the State of California comprising the first book. In like manner the card shown in Fig. 4, which card represents the State of Alabama, will bear at its 95 top the State names, Arkansas, Arizona and California. Within the space defined by the border 3 near the top of the card there is printed, as indicated by the numeral 5, certain data relating to the State represented 100

by that particular card and in the present instance this data consists of the date of admittance of the State to the Union, the area of the State, the number of counties, the 5 population, the capital, and the State nickname. Of course, this data may disclose other facts and may be more or less comprehensive as desired. Within the space defined by the border 3 below the data indicated by the numeral 5, there is printed a 10 map embracing the State represented by the card and its bounding States or bodies of water. For example, in the instance of the card shown in Fig. 3, the map embraces the 15 State of California represented by said card, as indicated by the numeral 6, and also the bounding States of Oregon, Nevada and Arizona as also lower California and the Pacific Ocean. In the instance of each card, 20 the map of the State which that card represents is printed in some distinctive color, as clearly shown in the several figures of the drawings so that the player may readily identify the cards which he holds.

25 Upon the reverse face of each card, which face is indicated by the numeral 7 and is, in other words, the space which is exposed to the view of the players other than the player holding that particular card in his hand, 30 there is printed, as indicated by the numeral 8, a map of the United States, the several States being indicated by numbers corresponding to the numbers borne by the respective State cards of the deck. For example, in the said map 8, the States California, Alabama, Arkansas and Arizona will each be designated by the number 1 and this number in each instance will be printed in a color corresponding to the color in which 35 it is printed upon the respective State card. In other words, upon the said map 8 the States in the order mentioned will be designated by the number 1 printed respectively in red, blue, black and yellow. There is 40 also printed upon the said reverse face of each State card, a representation of the great seal of the United States, as indicated by the numeral 9 and also a representation of the great seal of the State represented by 45 said card, as indicated by the numeral 10. These representations of the United States and State seals are respectively located in the upper right and upper left hand corners of the said face of each card so that when 50 the cards are held in the hand in the ordinary manner the representations of the State seals upon all of the cards will be exposed in view of the players other than the player holding the hand. Thus each player, if he 55 is familiar with the seals of the States of the Union, will be apprised of the State cards held by each of his opponents.

60 The reverse face of the card representing the District of Columbia, of course, bears the

seal of the District of Columbia in the upper 65 left hand corner of said face. The obverse face of the card representing the District of Columbia bears data concerning the District and corresponding to the data 5 upon the State cards and below this data the said 70 face of the card bears a representation of the United States Capitol. In the upper left hand corner there is printed upon the said face of the card a representation of a star, as indicated by the numeral 11.

75 There are several games which may be played with the cards embodying the present invention and following are the rules for playing one of such games.

80 Shuffle cards well and deal to the left one card at a time until each player has five cards (players will let their cards remain on table until dealer is through dealing) and lay the surplus pack face downward in the center of table. The player to the left 85 of dealer then starts the play by calling (to the left one player at a time) from each one or the other players a card giving number desired (not more than one card from each player at one play). If the player called 90 upon holds a card of the number called for, he will ask the caller what State that card represents. If the caller answers correctly the player will surrender card to caller, and draw one from the surplus pack to replace 95 the one surrendered, but if the player called upon does not hold a card of the number called for, or caller does not answer correctly he will say "not here" and caller calls on next player. If the caller fails to 100 get a card in the call and has no cards he wishes to hold for the count at the end of his play it is a blank play and the play passes on, but if he has a pair or book he wishes to hold for the count he lays them 105 on the table face up, these cards are called "held" for the count and cannot be called away from him. He then draws enough cards from the deck to give him five cards 110 in his hand and the play passes on.

115 The players will watch closely the deal and cards drawn from the surplus deck after the deal. The player, excepting the dealer, first seeing the "District" card and calling "District" can claim the "District privilege." The dealer stops the deal, places the "District" card back in the deck shuffles the cards and then continues the deal. If two or more players see and call "District" at the same time the card is placed back in the deck and there is no privilege allowed. The dealer is allowed one privilege for dealing and does not call "District" in the deal, but if the card comes to him in the deal and is not noticed by other players until 120 after he picks it up it gives him another privilege also.

125 To secure a privilege a player (other than

the dealer) must call "District" before the card is picked up either in the deal or draw.

There is no limit to the cards that can be drawn out of a player's hand by a player having the "District privilege" so long as the player calling can utilize the card to help make a pair or book in that play, and answers questions correctly. After the caller has passed one player he cannot go back to him again. When the "District" card appears in the draw it is the same as in the deal placed back in the deck and cards shuffled.

If the caller does not recognize a card in another player's hand that will help to complete a pair or book in his hand, he may call any card he wishes or disregard his own hand and draw any card, watching closely and calling a card that will break a pair or book held by that player and trying to prevent a player from completing a pair or book without calling for it.

A player having three cards of a book at the end of a play and wishing to take chances of getting the fourth, may do so by placing them face downward on the table in front of him and calling the number "down," such as fours down or sevens down, etc., which means that he is holding them for the fourth card. No player, but one having the "District privilege" and holding the fourth card and answering questions, can call these cards from him.

A player may hold as many cards in his hand as he wishes, but never less than five until cards are exhausted. Players must hold cards up so as the backs may be plainly seen by the other players.

Another game which may be played with the cards will now be described.

40 The rules of the first game govern in this game with the exception of the call and showdown.

Before the players start to play this game they will pick out a certain question to be answered in the call, such as "What is the nickname?" "What is the capital?" "What State bounds on the north, south, east or west?", or any question which may be answered by data on the face of the card.

50 The player starting a play will call for a card giving the name of the State he desires, and when required will point out that card in the player's hand. If the players decide that the question to be asked will be: "What is the number of counties?", the player called upon will ask that question, if caller answers correctly the card is surrendered, if not the play is the same as in the first game. The players will select a different question to be asked in the showdown. When a player gets a pair or book he wishes to hold for the count he lays it face up on the table so the rest of the players can see it, and calls, "pair" or "book up".

If the players select the question "What 65 year admitted to Union?"—the play proceeds, as for example:

Four players A, B, C and D are playing, B gets the book of twos and lays it down face up on the table and calls out "book up". A, 70 or the player to the right, picks the book up (A picks out any State he wishes to ask the question from) and asks, "What year was Delaware admitted to Union?" three times in quick succession. If B fails to answer, or answer correctly (by stating that Delaware is one of the thirteen original States) before A finishes calling, A passes to C, takes a different State and asks him the same question regarding that State, three 80 times, the same as he did B regarding Delaware. If C answers correctly the book goes to him and is shown down on the table to let all players see B's mistake. But if C fails to answer correctly A passes to D, takes 85 a different State and repeats the question. If D answers correctly the book goes to him but if not the book goes to A by default, and A shows it down on the table to let all the players see their mistake. 90

Asking the question three times in quick succession may be omitted if wished and the question asked only once.

A third game which may be played by the use of the cards is as follows: 95

The rules are the same as in the first and second games with the exception that the players do not select questions to be asked.

A player desiring a card from another player's hand will call for the card, naming 100 the State. The player called upon may ask the caller any question on the face of the card he wishes. If caller fails to answer correctly the play is the same as in the first and second games. The showdown is the 105 same as the call; a player asking questions from a pair or book may ask any question he wishes.

Still another game which may be played is in the nature of a handicap and may be 110 described as follows:

If a player or players familiar with the game wish to play with a player who is not, they may play the second or third game while the player who is not familiar plays 115 the first or second, allowing the showdown to pass the unfamiliar player while he is playing the first game.

The game consists of forty-nine points and in counting the points a pair is equal to one 120 point and a book to three points.

Having thus described the invention, what is claimed as new is:

1. A deck of playing cards certain cards of which bear upon one face a map and an 125 emblem and upon the other face a map of a subdivision of the territory shown by the first-mentioned map, the said emblem being

4
indicative of the territory shown in the second-mentioned map.

2. A deck of playing cards comprising a card representing the District of Columbia, 5 and twelve books of four cards each, each card of the books having upon one face a map of a State of the United States, an indicator common to all the cards of the same book, and means identifying the other cards

of the book, and having upon its other face 10 a symbol indicative of the State shown by said map and also a map of the United States, the indicators common to the cards of the respective books being duplicated on the respective States in the map of the United 15 States.

In testimony whereof I affix my signature.
HENRY W. WELLS. [L.S.]
